[57] **CLAIM**

The ornamental design for a fishing gaff holder, as shown and described.

DESCRIPTION

FIG. 1 is a perspective view of the fishing gaff holder in closed condition, it being understood that the broken lines are for illustrative purposes only and form no part of the claimed design;

FIG. 2 is a front view thereof in open condition;

FIG. 3 is a rear view of FIG. 2;

FIG. 4 is a right side view of FIG. 2;

FIG. 5 is a left side view of FIG. 2;

FIG. 6 is a top view of FIG. 2; and,

FIG. 7 is a bottom view of FIG. 2.
